His Attorney.

UNITED STATES PATENT OFFICE

2,495,638

WAFFLE IRON

Homer H. Miller, Bridgeport, Conn., assignor to
 General Electric Company, a corporation of
 New York

Application July 1, 1948, Serial No. 36,361

1 Claim. (Cl. 219—19)

1

This invention relates to electric waffle irons and it has for its object the provision in a waffle iron of an electric heating unit structure having improved electric connection means connecting the grid heating element and the electric supply conductors therefor.

This invention, in one form, comprises an endless support, preferably in the form of a ring, for the resistance conductor heating element of the heating unit. This support, in one section thereof, has a plurality of transverse passages joining the inner and outer sides of the support. The resistance conductor, which is mounted on the outer side of the support, has its terminals directed in toward the inner side thereof through separate ones of the passages, and the supply conductors for the heater enter these same passages from the inner side of the support. The supply conductors are joined to the terminals in the passages by any suitable connection means; are folded back, and directed outwardly to the outside of the support through other passage means.

For a more complete understanding of this invention, reference should be had to the accompanying drawing in which Fig. 1 is a side elevation view of an electric waffle iron embodying this invention; and Fig. 2 is a plan view of the heating unit used in the waffle iron of Fig. 1.

Referring to the drawing, this invention has been shown in one form as applied to an electrically heated waffle iron comprising a base 1 to which the lower heating grid 2 is attached. An upper heating grid 3 is fixed within the upper casing 4. This casing is hinged at the rear of the base 1 by means of a hinge 5 and is provided in front with a handle 6.

The upper grid 3 is heated by means of a heating unit comprising a coiled resistance conductor 7 mounted upon the outside periphery of an electrically insulating supporting brick 8. This brick, as shown, has a ring shape, the ring having inner and outer concentric cylindrical walls. Also, the brick has two series of spaced apart projections 9 and 10 above and below the resistance conductor which function to hold the conductor in position with respect to the brick, the projections of the upper row 9 preferably being positioned opposite the spaces between the projections of the lower row 10.

The resistance heater element 7 is in the form of a broken ring with its two terminal ends 11 and 12 being adjacent to each other and being directed from the outer side of the ring back toward the inner side in substantially parallel

2

relation with each other through horizontal tubular passages 13 and 14 formed in the ring.

Also entering these passages 13 and 14, but from the inner side of the ring are a pair of electrically insulated supply conductors 15 and 16. And located within the two passages respectively are electric connectors 17 and 18 which function to mechanically and electrically connect the heater terminals 11 and 12 with the conducting wires of the supply conductors 15 and 16. The connectors 17 and 18 may be of any suitable, well-known construction.

Inside the ring the supply conductors 15 and 16 are directed upwardly toward the top of the ring from the two passages 13 and 14 and thence are directed from the inner side of the ring to the outer side thereof through a pair of horizontal passages 19 and 19a respectively, which passages, as shown, are open at the top. From the outside of the ring, these conductors are directed and connected to the heating element (not shown) or the lower grid 2 and to the usual twin supply terminal pins (not shown).

The open-top passages 19 and 19a are closed by means of a circular plate 20. This plate is the bottom wall of a pan-shaped clamping plate 21 which, at the center is attached to the upper grid 3 by means of a screw 22 entering a boss 23 which is formed integrally with and which extends upwardly from the grid. The plate 20 at its peripheral edge is provided with a down-turned flange 24 which is spaced from, but which covers the resistance heater 7. The plate 22 functions not only to close the passages 19 and 19a, but it also functions to clamp the heater brick 8 and the heater 7 supported thereby to the upper grid. The pan at the point opposite the supply conductors 15 and 16 is provided with an opening 25 registering with the passages 19 and 19a and through which the conductors 15 and 16 pass to their terminals (not shown).

By virtue of the fact that the conductors 15 and 16 are folded back over themselves, so to speak, through the passages 19 and 19a, the conductors are anchored to the heater brick; that is, the looped sections formed in the conductors, as they are folded back on themselves and thence run to the outside of the heater brick, function to anchor the conductors to the brick.

50 What I claim to be new and desire to secure by Letters Patent of the United States is:

A waffle iron comprising a grid, a heater for said grid having a ring support which has top and bottom walls, and inner and outer cylindrical walls and formed with two enclosed tubular pas-

sages connecting said inner and outer cylindrical walls and two other passages opened at the top also connecting said inner and outer cylindrical walls, a resistance conductor mounted on said outer cylindrical wall and having its two terminal ends respectively directed in toward said inner cylindrical wall through said two enclosed transverse passages, a pair of electric supply conductors directed into said two passages from said inner cylindrical wall, means in said two passages connecting said conductors with said terminals, said conductors being folded back and directed through said other two passages from which they emerge through said outer cylindrical wall, a clamping plate engaging said ring support and covering said other two passages, and means attaching said plate to said grid so as to secure said support thereto.

HOMER H. MILLER.
